[57] CLAIM

The ornamental design for a personal video communicator, as shown and described.

DESCRIPTION

FIG. 1 is a front, top and right side perspective view of a personal video communicator showing our new design;

FIG. 2 is a rear elevational view thereof;

FIG. 3 is a left side elevational view thereof; and,

FIG. 4 is a bottom plan view thereof.

The broken line showing of an Antenna in FIGS. 1 and 3 is for illustrative purposes only and forms no part of the claimed design.

FIG. 1

*FIG. 2**FIG. 3**FIG. 4*
